UNITED STATES PATENT OFFICE.

EVA J. McKINNEY, OF HALLSVILLE, ILLINOIS.

WAIST AND SKIRT SUPPORTER.

No. 853,646.

Specification of Letters Patent.

Patented May 14, 1907.

Application filed October 6, 1906. Serial No. 337,757.

To all whom it may concern:

Be it known that I, EVA J. McKINNEY, a citizen of the United States, residing at Halls-ville, in the county of Dewitt and State of Illinois, have invented certain new and useful Improvements in Waist and Skirt Sup-porters, of which the following is a specifica-tion.

This invention relates to skirt supporters 10 designed chiefly for preventing ladies' and misses' skirts from sagging, and the upward creeping of the waist.

In accordance with this invention, the back of ladies' waists at the waist line and 15 the skirt bands are provided with washable tape pieces containing eyelets or buttonholes, and a waist band, or waist band with shoulder tapes, is provided with headed studs secured thereto in a unique manner and adapt-ed 20 to pass through the eyelets of the bands of the skirts and shirt waist so as to hold said parts in adjusted and proper position. Also said washable tape pieces containing said eyelets or buttonholes may be attached at the 25 waist line of men's and boys' shirt waists, and so adjusted as to be supported by shoulder tapes and waist band with said headed studs properly arranged upon said waist band. Said eyelets or buttonholes may be properly 30 arranged in a tape to be attached to the inner side of men's and boys' pants waist band.

For a full description of the invention and the merits thereof and also to acquire a 35 knowledge of the details of construction and the means for effecting the result, reference is to be had to the following description and accompanying drawings, in which:

Figure 1 is a detail perspective view showing the application of the invention. Fig. 2 40 is a detail perspective view of a tape constituting a waist band for a skirt or shirt waist showing the manner of providing the eyelets or buttonholes therein.

The waist band 1 may be of tape or other 45 textile or pliable strip and is adapted to be secured about the waist in any convenient manner. At one or more points in the length of the waist band is located a stud 2, the same having a head and a backplate and hav-ing the general appearance of a collar button 50 of well known formation. Usually, a series of three such studs are provided and ar-ranged so as to appear, one at the back of the wearer at a central point and the other two at the sides thereof.

The waist band 5 of the shirt waist and skirts is provided with one or more eyelets or buttonholes 7, the same being reinforced by pieces of tape or cloth 8 secured thereto pref-erably by means of the stitching, reinforcing 60 and finishing the eyelets or buttonholes. The reinforcing pieces 8 also serve to provide tabs or grips to be pulled upon when it may be required to disconnect one or more eye-lets or buttonholes from the corresponding 65 headed stud.

The eyelets being in a double washable tape, which tape is inserted through an incision cut as for a buttonhole the same size as the eyelet in the back of all waists at the 70 waist line, and in the bands of all skirts. The eyelets or buttonholes being adjustable to all parts by means of drawing one side of the tape through the incision therein and stitching said eyelet or buttonhole tape 75 around the outer edge firmly to material in which the incision is made. Said eyelets being so adjusted to correspond with the position of the stud upon which it is to be sup-ported.

Having thus described the invention, what is claimed as new is:

In combination with material provided with a buttonhole, a reinforcing piece at-tached to the material by means of the stitch-ing finishing said buttonhole and having its 85 end portions loose to provide tabs or pull pieces.

In testimony whereof I affix my signature in presence of two witnesses.
